SIGNALING APPARATUS

Florentino G. Troisi, Pittsburgh, Pa.

Application December 3, 1936, Serial No. 114,012

20 Claims. (CL. 179—1)

My invention relates to signaling apparatus and has particular relation to apparatus for transmitting messages and signals between an operator at a central station and a plurality of operators in distributed stations such as diving suits, for example.

It is an object of my invention to provide apparatus for transmitting messages from one diver to another which shall be heard by a central station operator and for transmitting both messages and signals from the central station operator to any or all of the divers.

Another object of my invention is to provide a simple and inexpensive system for transmitting amplified signals and messages from a central station to any or all of a plurality of distributed stations and from any one distributed station to any or all of the other distributed stations and the central station.

20 A further object of my invention is to provide apparatus for transmitting signals from a central station to a plurality of distributed stations located in diving suits under water, that shall incorporate an oscillation generator for signaling purposes and in which the oscillation generator shall be so connected as to involve no danger to the operator located in the diving suit.

Still another object of my invention is to provide a system incorporating an amplifier for intercommunications between a plurality of stations that shall be so contrived that it shall be possible to transmit messages between the stations when the amplifier system is for one reason or another out of operation.

35 An incidental object of my invention is to provide a switching element provided with contacts, to be connected to two points at different potentials, in which the contacts shall be rigidly mounted.

40 Another incidental object of my invention is to provide a plug, of the type that is inserted in a jack to complete an electrical connection, that shall be particularly adapted for making such a connection in a watertight enclosure, and which shall not require accurate positioning of the plug within the jack.

A further incidental object of my invention is to provide a watertight connection for a life-line of the type that incorporates electrical conductors.

50 More specifically stated it is an object of my invention to provide apparatus for signaling between a central station located above water and a plurality of distributed stations located in diving suits under water by the operation of which it shall be possible to transmit clear and audible

signals without danger of injury by electrical shock or otherwise to the operators in the diving suits.

According to my invention I provide a signaling system in which self-energizing batteryless sound conversion units were disposed at the distributed stations in the diving suits and preferably at the central station. Sound conversion units of the type that I prefer to utilize are described in my Patent #1,770,821, dated July 15, 1930, for Telephonic apparatus for deep sea diving. Each of the units includes a diaphragm, an armature, a permanent magnet in the field of which the armature vibrates and a voice coil which varies the field of the permanent magnet to provide a vibratory force. The unit may accordingly be utilized either as a receiver or a transmitter of sound. In the practice of my invention one of the units is at any time utilized to transmit a message or signal to one or more of the remaining units. The sound impressed on the transmitting unit is amplified before being reproduced; a single amplifier is used for all of the units.

To properly interconnect the sound conversion units and the amplifier a plurality of switches 25 preferably one for each of the distributed stations are provided. The switches are preferably located at the central station and are operated by the central station attendant. The distributed station switches are operable to connect the sound conversion units at the distributed stations either to the input or the output of the amplifier. When a sound conversion unit is connected to the input of the amplifier the operator at the corresponding station may speak through his sound 30 conversion unit to the operator of any station in which the sound conversion unit is connected to the output of the amplifier. The central station connections are such that the attendant at the central station hears the conversation between 35 the operators at the distributed stations.

Corresponding to the central station a switch is provided that may be operated by the central station attendant to enable him to talk to the operators in the distributed stations. When the central station switch is in a position for the transmission of messages from the central station, the central station sound conversion unit is connected to the input of the amplifier and the distributed station conversion units are connected to 45 the output of the amplifier regardless of whether the switches corresponding to the latter are in a position for transmission or reception.

Should the central station attendant desire to attract the attention of the divers he throws the 55

central station switch in another direction causing the operation of a signaling oscillation generator connected to the input of the amplifier. At the same time the sound conversion units at 5 the distributed stations are connected to the output of the amplifier.

If the amplifier should become inoperative for one reason or another the system does not necessarily become inoperative. As has been mentioned above the sound conversion units are of 10 the batteryless type such as are used in sound-powered telephone systems. When the amplifier becomes inoperative the sound conversion units are all connected in parallel and the apparatus 15 ratus operates sound powered.

In the practice of my invention plug and jack combinations are utilized for making connections. In accordance with a further aspect of 20 my invention I provide a plug having contacts to be connected to at least two points between which a different of potential exists. The plug is 25 analogous to those of the prior art, but is of considerably more rigid structure and has other advantages which will be apparent from the following description:

It comprises a central longitudinal member on 30 which cylindrical contact members are disposed. The contact members are separated by cylindrical insulating members. The surfaces of engagement between the insulating members and the contact members are at an angle different than 90° to the axis of the longitudinal member and therefore lateral motion of the cylindrical contact and insulating member is prevented.

When apparatus constructed according to my 35 invention is used, the plug cannot be locked in a single position since the plug and jack are located under water during normal operation and must be enclosed in a water-tight chamber. To 40 prevent the contacts of the plug from becoming disengaged from the contacts on the jack, I construct the former contacts with considerable length.

The electrical conductors whereby the signals 45 are transmitted between the different distributed stations and the central station are imbedded in the diver's life-line. The life-line and the conductors are connected to the diving suit through a water-tight plug assembly which comprises a 50 suitable sleeve into which a nut is screwed compressing packing and washers suitably disposed. The life-line is secured to a block mounted in the sleeve by sealing the core of the life-line in an opening in the block.

The novel features that I consider characteristic 55 of my invention are set forth with particularity in the appended claims. The invention itself, however, both as to its organization and its method of operation together with additional 60 objects and advantages thereof will best be understood from the following description of specific embodiments when read in connection with the accompanying drawings in which:

Fig. 1 is a view in perspective showing the 65 essential elements of an embodiment of my invention:

Fig. 2 is a view partly in section and partly in 70 side elevation showing the cable utilized in the practice of my invention and the structure whereby the cable is coupled to the apparatus at its terminals;

Fig. 3 is an exploded view showing the essential 75 features of the apparatus whereby the cable is coupled at its terminals;

Fig. 4 is a view in perspective showing the jack utilized in the practice of my invention;

Fig. 5 is a view in section showing a plug constructed in accordance with my invention;

Fig. 6 is a diagrammatic view showing the circuit utilized in the practice of a preferred embodiment of my invention; and

Fig. 7 is a diagrammatic view showing the principal elements of the circuit utilized in the practice of a modification of my invention. 10

In Fig. 1 the essential aspects of the apparatus located at the central station 9 and at one of three distributed stations 11 is illustrated. At the central station a closed container 13 is provided and an amplifying and signaling unit 15 together with a plurality of controlling switches 17, 19, 21, 23, and 25 are located within the container. The switches are operated by handles which project from the upper surface 27 of the container 13. The cover 29 of the container is 15 suitably hinged to the upper surface thereof and supports a loud speaking sound conversion unit 31. In the back 33 of the container 13 a plurality of suitable connecting receptacles 35, 37, 39, 41, and 43 for plugs are provided. Power is 20 supplied to the container 13 by plugging a cable 45 from a suitable power source 46 into one of the upper receptacles 35. The lower receptacles 39, 41, and 43 are utilized for connecting sound conversion units 47, 49, and 51 located at the 25 distributed stations to the central station. 30

The conductors 53 and 55 connecting the central station 9 and the distributed stations are imbedded in the diver's life-line 57 and are connected to plugs 59 at both ends. The plugs 59 are 35 mounted in coupling member 61 at both ends; and when the apparatus is in operation, the plugs are inserted in jacks 63 and the coupling members 61 engage cooperating coupling members 65, 67, 69, and 71 provided for the receptacles 39, 41, and 43 and at the distributed stations such as 11. The distributed station coupling member 71 is mounted near the center of the rear of the diver's helmet 73. The diver's sound conversion units 47, 49, and 51 are secured 40 within the helmet 73 opposite to the position of the diver's mouth. They are connected to the jacks within coupling member 71 by a cable 75 which is clamped along the upper portion of the helmet. While the life-line coupling member 45 61 is tightly screwed to the member 71 in the helmet 73, the life-line 57 is not suspended from this alone, but passes through a suitable clamp 77 in the breast plate 79 of the diving suit.

In Fig. 1 a single diving sound conversion unit 55 is shown as connected. The container 13 at the central station is provided with two additional receptacles 39 and 41 adapted to receive cable 60 couplings similar to that shown and in the ordinary practice of my invention any number up to three connecting outlets are in use. When any of the receptacles 35, 37, 39, 41, and 43 are 65 not in use they are protected by closed hexagonal caps 81 which are screwed over the receptacles and which, when the receptacles are in use, are 70 suspended from chains 83 extending from the back 33 of the container 13.

The life-line 57 and its coupling members 61 are 75 shown in detail in Figs. 2 and 3. The body of the life-line is composed of rubber or other flexible insulating material 85 strengthened by a stranded steel core 87 imbedded in its center. The electrical conductors 53 and 55 are imbedded 80 in the insulating material 85 between the core 87 and the outer surface. In the preferred prac- 85

5 tice of my invention a pair of conductors is utilized for each terminal connection. The conductors of each pair are connected together at the upper and lower ends. The coupling member 61 comprises a sleeve 89 into which the life-line 57 extends. The sleeve 89 is provided with an inwardly-projecting flange 91 that supports a cylindrical block 93. The block 93 has a conical opening 95 coaxial with the outer surface thereof 10 and, before the plug is disposed on the flange 91, the stranded core 87 of the life-line 57 is skinned and projected through the opening where the individual strands are spread out and disposed around the periphery of the opening 95. A screw 15 97 is then driven into the core wires and the whole conical opening is filled with solder.

20 At its lower end 99 the sleeve 89 is threaded internally and directly above the thread, the opening in the sleeve tapers towards a narrow neck 101 that terminates at the flange 91. Before the life-line 57 is inserted in the sleeve 89 an externally threaded hexagonal nut 103 and a packing gland 105 are slipped over it. When the core 87 has been fastened to the block 93 25 the block is set on the flange 91. The packing gland 103 is then inserted in the tapered portion below the neck 101 and after the life-line has been pulled taut, the externally threaded nut 103 is engaged with the threads 99. When the nut 103 is screwed tightly, it compresses the packing 30 105 and renders the lower portion of the life-line coupling 61 water-tight.

35 When the end of the life-line 57 that is to be connected to the coupling-member 61 is skinned and otherwise prepared for the connection, it is trimmed in such manner that the conductors 53 and 55 extend considerably beyond the end of the stranded steel core. Hence, when the block 93 is seated on the flange 91, the conductors 53 and 40 55 are slipped through grooves 107 milled into the block. The projecting ends of the wires composing each pair 53 and 55 are then twisted together and soldered into the terminal lugs 109.

45 The plug 59 is in its geometric structure not unusual. It comprises a composite longitudinal cylindrical member 111 extending above a flanged portion 113 below which the plug terminals 115 and 117 project. The terminal lugs 109 are secured to the terminals 115 and 117 and the plug with the lugs attached thereto are disposed within the sleeve 89, the flanged portion 113 resting 50 on a leather washer 129 which in turn rests on an internal flange 121 located near the upper end of the sleeve. An insulating washer 119 insulates the terminal lugs 109 from the block 93 and screw 55 97. Before the plug 59 and its attachments are inserted in the sleeve 89 the portion of the sleeve between the block 93 and the upper flange 121 is filled with melted wax 123 and the contacts 60 115 and 117 and the lugs 109 are immersed in wax. The upper end 125 of the sleeve 89 is threaded and an externally threaded nut 127 is provided to engage this thread. The nut 127 rests on and compresses a leather washer 130 disposed on the flanged portion 113 of the plug 59. The washers 129 and 130 thus render the upper 65 portion of the coupling member 61 water-tight.

70 In its upper region the sleeve 89 is provided with an external flange 131. Before the life-line is permanently connected to the coupling member 61, it is slipped through a ring 141 and a nut 133 internally threaded along only a portion of its length 135. In its unthreaded portion 137, the nut 133 is provided with an internal flange 139 75 which engages the external flange 131 on the

sleeve 89 preventing the nut from slipping off the end of the sleeve. After the sleeve 89 is connected to the life-line 57, the nut 133 is raised to a position near the external flange 131 on the sleeve and is prevented from sliding back 5 of the sleeve 89 by the ring 141 which is pinned to the outer surface of the sleeve below the nut.

10 In accordance with my invention the receptacles 35, 37, 39, 41, and 43 and the coupling member 61 are provided with externally threaded cylindrical portions 143 which the nut 133 is adapted to engage. When a plug 59 is to be inserted in one of the receptacles, the nut 133 is screwed onto the threaded cylinder 143 and thus the life-line 51 is tightly coupled to the apparatus to which the plug is connected. When the equipment is not in use it is desirable that the coupling member 61 be protected and for this reason a cover 145 adapted to be screwed into the nut 133 is added to the equipment.

15 The jack 63 utilized in accordance with the practice of my invention is shown in Fig. 4. It comprises a semi-cylindrical block 147 of insulating material such as a phenolic condensation product having an axial opening 149 therethrough and provided on its plane face 151 with a bracket 153 having the form of an E in end view. The legs 155, 157, and 159 of the E are plate-shaped and form grooves parallel to the face 151. The whole unit may be machined from a rectangular 20 piece of insulating material of the proper dimensions. In machining the element the grooves between the plates 155, 157, and 159 are cut so deeply that they open into the opening 149 and spring contact elements 161 and 163 secured to 25 the body of the E on both sides extend into the grooves and therefore project into the opening 149. The block 147 is bolted to a metal plate 165 provided with a hollow stem 167, the opening in which is coextensive with the opening 149. 30 A leather gasket 169 is then slipped in the stem below the plate 167. Jacks similar to that described above are mounted in the receptacles 35, 37, 39, 41, and 43 with the gasket 169 outward. The plug 59 is slipped into the jack through the 35 opening in the stem 165 and opening 149 and when the plug is so inserted the upper end of the sleeve 61 and the upper end of the nut 127 coextensive therewith rests against the gasket 169. When the nut 133 is screwed tightly in place, the 40 whole coupling assembly is water-tight. As the gasket 169 wears or gives, the plug 59 may move inwardly or outwardly. Accordingly the plug cannot be of precisely the usual structure which is locked in a predetermined position.

45 The plug 59 is shown in detail in Fig. 5. It comprises a bolt 171 threaded near the top 173 and provided with a head 175 at its lower end. The terminals 115 and 117 are of L section and the base 177 of one terminal 115 rests directly on the bolt head 175. On the terminal base 177 an insulating washer 179 is disposed and an insulating tubular member 181 over the bolt extends upward from the washer. The base 183 of the other terminal 117 of the plug 59 is sweated onto a metallic tubular member 185 through which the insulating tubular member 181 is slipped. The two terminals 115 and 117 are thus insulated from each other.

50 On the base 183 is an insulating washer 187 and an insulating shell 189 extends upward from the washer. A metallic member 199 provided with the comparatively heavy flange 113 is mounted on the insulating shell 191. The insulating shell 189 is provided at its upper end with a ring- 55

shaped projection 193 having surfaces 195 and 197 at an obtuse angle to the axis of the shell. The conducting member 191 of the assembly is provided with an upper surface corresponding to the lower surface 197 of the ring 193 and firmly engages the ring at the top. The washer 187 insulates the flange 113 from the terminal 117.

The metallic shell 185 is not of simple structure, but is provided with a ring-shaped projection 199 of wing-cross section which functions as the contact connected to terminal 117. The contact 199 is provided with a bevelled surface at the bottom to correspond to the surface 195 of the insulating ring projection 193. Its upper surface 201 is also bevelled.

The inner insulating member 181 extends to a point within the contact 199. Into the upper portion 203 of the contact 199 the stem 205 of an insulating member 207 of T section which is slipped over the bolt 171 is engaged. The T section member 207 is provided near its center with the ring-shaped cross member 209 having bevelled surfaces at the top and bottom. The lower bevelled surface is designed to engage the corresponding upper surface 201 of the contact 199. The upper surface 211 engages another contact member 213 which is threaded to engage the threads 173 on the bolt 171. The bolt 171 is tightly screwed into the upper contact member 213 and thus good contact is obtained between the various connecting metallic elements. The upper contact member is provided with a reamed opening 215 into which solder is poured and permitted to harden to make certain that the assembly is rigid. The contact members 199 and 213 are both comparatively long so that when the leather gasket 169 mounted on the jack 63 wears the plug contacts continue to engage corresponding jack contents 161 and 163.

The preferred electrical circuit utilized in the practice of my invention is illustrated in Fig. 6. Power is supplied to the system preferably from the direct current generator 46 which is customarily present on the tug or boat from which the divers are launched. The generator is connected through a pair of contacts 215 of the switch 17 to the terminals of a voltage dividing potentiometer 217 whereby the various potentials are supplied to a two-stage amplifier 219 and an oscillation generator 221 provided for signaling purposes. The switch 17 is also provided with a pair of contacts 223 which connect the output coil 225 of the amplifier system 219 through the switch 25 which determines the direction of transmission of the signals and messages. The movable contacts 215 and 223 of the switch 17 are operated together and when the switch is in one position engage the corresponding fixed contacts 227 and 229 respectively at the same time. The switch may also be operated to another position where movable contacts 223 engage a pair of fixed contacts 231 connected across the input coil 233 of the amplifier 219.

As has been explained the amplifying and signaling unit 15 and the control switches 17, 19, 21, 23, and 25 are mounted in the container 13 located at the central station while the sound conversion units 47, 49, and 51 are mounted in the helmet 11 of the diving uniforms. The switches 19, 21, and 23 are each associated with a sound conversion unit 47, 49, and 51 respectively. Each of these switches 19, 21, and 23 may be thrown either to the "transmit" position or to the "receive" position, thus enabling the operator to control the flow of messages or signals.

The amplifier 219 is of the ordinary two-stage type in which a pair of pentode amplifier tubes 235 and 237 are utilized. The signal or message energy is impressed on the input coil 233 which is the primary of a suitable audio-transformer 239. The output circuit 241 of the first stage of the amplifier is resistance-capacity coupled to the input circuit 243 of the second stage and the output energy of the second stage is delivered through a suitable audio-output transformer 245 of which the coil 225 is the secondary. The usual resistors and capacitors functioning to properly couple the amplifier and to properly supply and filter the required tube potentials are provided, but they are well known in the art and need not be discussed here.

The apparatus provided in accordance with my invention is utilized principally for transmitting messages. However, under certain circumstances it becomes necessary to transmit a signal, that is to say, a note of some kind to indicate to the divers that a certain event is to take place. In accordance with my invention the oscillation generator 221 is utilized to provide the signal note. The oscillation generator 225 comprises the usual three-electrode tube 247 in the grid circuit 249 of which a resonant network 251 tuned to the frequency of the note utilized is connected. The grid circuit 249 is inductively coupled to the anode circuit 253 through a transformer 255, the primary of which is the coil 257 utilized in the tuned network 251. The secondary 259 of the transformer 255 is connected to the anode 261 of the tube 247 at one terminal and at the other terminal is adapted to be connected to the positive pole 263 of the source 46 when the operator's switch 25 is thrown to the signal position.

The output of the oscillation generator 221 is applied to the input of the first amplifier stage through an inductive connection to the primary 233 of the input transformer 239. Since the primary of the input transformer may be conductively connected to the sound conversion units 47, 49, and 51 in the diving suits, it is desirable to avoid any direct connection between the anode 261 and the input circuit for the anode is at a dangerously high voltage and accidental connection to the diving suit may be disastrous. Accordingly a separate output coil 265 is utilized for the oscillation generator and it is completely insulated both from anode circuit 253 of the tube 247 and from the grid circuit 249.

Now assume that the power control switch 17 is in the lower position, that is the position in which the movable contacts 215 and 223 engage the fixed poles 227 and 229. Assume also that it is desirable that one of the divers, say the one corresponding to the sound conversion unit 47, desires to talk to the diver corresponding to the sound conversion unit 51. In such a case the switch 19 corresponding to the former is thrown upwardly to the "transmit" position and the switch 23 corresponding to the latter is thrown downwardly to the "receive" position. When the transmitting diver speaks speech current flows from the upper terminal of the sound conversion unit 47 through the conductor 53, the left hand movable contact 267 of the switch 19, a conductor 269, the lower central movable contact 271 on the right of the operator's switch 25, a corresponding fixed contact 273, a conductor 275, the upper central movable contact 277 on the right of the operator's switch, a corresponding fixed contact 279, a conductor 281, a conductor 283, 75

the primary 233 of the input transformer 239, a conductor 285, a conductor 287, an upper left hand central fixed contact 289 of the operator's switch, the corresponding movable contact 291, 5 a conductor 293, a lower left hand central fixed contact 295 of the operator's switch, the corresponding movable contact 297, a conductor 299, a movable contact 301 of the transmitting diver's switch, the conductor 55 to the lower terminal 10 of the sound conversion unit.

The speech of the transmitting diver is amplified by the amplifier 219 and the output of the amplifier is connected to the sound conversion unit 51 of the receiving diver. The latter circuit 15 extends from the upper terminal of the secondary 225 of the output transformer 245 through a conductor 303, a movable contact 305, of the receiving diver's switch 23, the conductor 53, the sound conversion unit 51, the conductor 55, a movable contact 307 of the receiving diver's 20 switch, a conductor 309 to the lower terminal of the output transformer's secondary.

It is to be noted moreover that the operator at the central station also hears the conversation 25 between the two divers. This occurs because the secondary 225 of the output transformer 245 is connected to the operator's sound conversion unit 31 through the contacts 223 of the switch 17. The circuit for the operator's unit 31 extends from the 30 upper terminal of the output secondary 225 through the conductor 303, a conductor 311, a movable contact 223, a conductor 313, a conductor 315, an upper right-hand fixed contact 317 of the operator's switch 25, the upper right-hand 35 movable contact 319 of the operator's switch, a conductor 321, the operator's sound conversion unit 31, a conductor 323, the upper left-hand movable contact 325 of the operator's switch, a corresponding fixed contact 327, a conductor 329, a conductor 331, a movable contact 323, a conductor 333, the conductor 309 to the lower terminal of the secondary of the output transformer.

It is to be noted that when the divers transmit 40 messages to each other, the operator's switch is in the neutral position. Should the operator desire to transmit a message he throws his switch 25 upwardly to the "talk" position and the divers' switches either to the "transmit" position or the "receive" position. In general the latter switches 45 will be in one of these positions since the divers have been talking to each other. However, with the operator's switch in the "talk" position the divers' sound conversion units 47, 49, and 51 are all connected to the output coil 225.

With the operator's switch in the "talk" position his speech currents flow to the primary 233 of the input transformer 239 in a circuit which extends from the upper terminal of the operator's sound conversion unit 31 through the conductor 60 323, the upper left-hand movable contact 325 of the operator's switch 25, a corresponding fixed contact 335 now engaged, the conductor 285, the primary 233 of the input transformer 239, a conductor 283, an upper left-hand fixed contact 337 of the operator's switch now engaged, the corresponding movable contact 319, the conductor 321 to the lower terminal of the sound conversion unit.

The divers' sound conversion units such as the unit 51 for which the switches are thrown for 65 reception are connected in the output of the amplifier 219 as is explained hereinabove. The divers' sound conversion units such as the unit 47 for which the switch is thrown to the transmission side are now also connected to the output of the amplifier. In the latter case the circuit of the

unit extends from the upper terminal of the secondary of the output transformer through the conductor 303, the conductor 311, a movable contact 229 of the switch 17, the conductor 313, a central upper fixed contact 339 on the right of the operator's switch 25, the corresponding movable contact 271, the conductor 275, a central lower fixed contact 341 on the right of the operator's switch, the corresponding movable contact 271, the conductor 269, the movable contact 267 of the switch 19 thrown to the "transmit" side, the sound conversion unit 47, the movable contact 301, the conductor 299, the central lower movable contact 297 on the left in the operator's switch, the corresponding fixed contact 295, the conductor 293, the upper central movable contact 291 on the left in the operator's switch, a corresponding fixed contact 343 now engaging the movable contact, the conductor 331, a movable contact 323 of the switch 17, the conductor 333 to the lower terminal of the secondary 225 of the output transformer 245.

If it becomes necessary for one reason or another to signal to the divers, the operator throws the operator's switch 25 to the "signal" 25 position immediately connecting the anode 261 of the oscillation generator tube 247 to the positive terminal of the source through the lower left-hand movable contact 345 of the operator's switch. The oscillation generator 255 begins to operate 30 and produces a signal which is supplied to the input of the amplifier 219 and after being amplified is impressed on the diver's sound conversion units 47, 49, and 51 regardless of whether they are thrown to the transmit or receive position. Moreover the operator also hears the signal transmitted.

The divers' sound conversion units which are thrown for reception are connected to the output of the amplifier as explained above. Those thrown to the transmission side are connected for reception through conductors connected to the secondary 225 of the output transformer 245 through the contacts 223 of switch 17 and through the lower central contacts 247 and 249 of the operator's switch 25. The operator's sound conversion unit 31 is also connected to receive the signal from the output of the amplifier 219 through the contacts 223 and the upper movable contacts 319 and 325 of the operator's switch which are in the position shown in the drawings since the switch is thrown to the signal position.

Should the amplifier 219 become incapacitated for one reason or the other, the system may be sound powered. In this case the switch 17 is thrown upward to the sound powered position connecting the sound conversion units 47, 49, and 51 in parallel through the movable contacts 223 and the fixed contacts 331. For sound power operation the divers' switches 19, 21, and 23 must be thrown to the "transmit" position and the operator's switch 25 must be at neutral. In this case the units 47, 49, and 51 are all connected to the conductors 283 and 285 leading to the input of the amplifier 219. The circuit is completed through the contactor 223 and conductors 313 and 331. The operator may listen by plugging in a receiver to a receptacle connecting the receiver in parallel with the other sound conversion units. Since all of the sound conversion units are of the batteryless telephone type provided with permanent magnets the sound produced by one of the operators speaking in his sound conversion unit operates the other units.

In the apparatus shown in Fig. 6 the transition 75

from the power operated to the sound powered system is by hand. This is the most common method of operation. On occasions it may be desired to cause the transition to take place automatically in response to the failure of the amplifier unit or certain of its parts. This object is accomplished as shown in Fig. 7 by providing a relay 351, the exciting coil 353 of which is connected across the part of the amplifier unit, to the failure of which the automatic response is to take place. The most common source of failure is the cathode circuit and the coil 351 is indicated as connected in the circuit. The relay is of the high impedance type so that the amplifier 219 is not shortcircuited. So long as the amplifier is energized the exciting coil 353 of the relay is energized and the relay is in a position in which one of its movable contacts 355 engages a plurality of fixed contacts 357 connected to the amplifier and sound units. The fixed contacts 357 correspond to the fixed terminals 227 of the power switch 17. The movable contacts 355 of the relay are in turn connected to the terminals of the generator in the same manner as contacts 215.

Another set of movable contacts 359 is normally engaged with corresponding fixed contacts 361 connected to the amplifier output circuit. The movable contacts are connected to the operator's switch 25 in a manner similar to that in which the movable contacts 223 are connected to this switch. When the amplifier becomes de-energized by reason of some defect the relay 351 is de-energized and the armature drops disconnecting the amplifier and sound units from the generator and the amplifier output from the operator's switch 25. At the same time the lower set of movable contacts 359 of the relay engages another set of fixed contacts 363 which are connected to the amplifier input thus connecting the sound conversion units in parallel.

Although I have shown and described certain specific embodiments of my invention, I am fully aware that many modifications thereof are possible. My invention, therefore, is not to be restricted except in so far as is necessitated by the prior art and by the spirit of the appended claims.

I claim as my invention:

1. A system of communication between a central station and a plurality of distributed stations comprising a sound conversion unit at each distributed station and at said central station, switching means individual to each distributed station providing for the transmission of a message from any one of said distributed stations to any other of said distributed stations and switching means associated with said central station providing for the reception of said messages by said central station and for the transmission of a message from said central station to said distributed stations, the last said switching means operating to permit the transmission of a message to said distributed stations when the switching means individual to said distributed stations is either in the transmitting or receiving position.

2. A system of communication between a central station located above water and a plurality of distributed stations located in diving suits under water comprising unitary sound conversion units mounted in said diving suits in a position such that sound may be conveniently impressed thereon for transmission or received therefrom, sound conversion means located at said central station, switching means individual to each said sound conversion unit and located

at said central station providing for the transmission of a message from any one of said distributed stations to any other of said distributed stations and switching means associated with and located at said central station providing for the reception of the said message from any one station to any other station and for the transmission of a message from said central station to said distributed stations, the last said switching means operating to permit the transmission of a message from said central station to any distributed station when the switch individual to said station is either in the receiving or transmitting position.

3. A system of communication between a central station located above water and a plurality of distributed stations located in diving suits under water comprising unitary sound conversion units mounted in said diving suits in a position such that sound may be conveniently impressed thereon for transmission or received therefrom, signaling means, switching means individual to each said sound conversion unit and located at said central station providing for the transmission of a message from any one of said distributed stations to any other of said distributed stations and switching means associated with and located at said central station providing for the reception of the said message from any one station to any other station and for the operation of said signal means to transmit a signal from said central station to said distributed stations, the last said switching means operating to permit the transmission of a signal from said central station to any distributed station when the switch individual to said station is either in the receiving or transmitting position.

4. A system of communication between a central station located above water and at least one distributed station located in a diving suit under water comprising a sound conversion unit mounted in said diving suit, signaling means including a discharge device having an anode, a cathode, and a control electrode, circuits between said anode and said cathode and said control electrode and said cathode inductively coupled to each other, means for connecting a dangerously high potential in one of said circuits, and a circuit for deriving energy from said first-named circuit, said last-named circuit being capable of metallic connection to said sound conversion unit and being insulated against metallic electrical conduction from said anode-cathode circuit.

5. A system of communication between a central station located above water and at least one distributed station located in a diving suit under water comprising a sound conversion unit mounted in said diving suit, signaling means including a discharge device having an anode, a cathode, and a control electrode, circuits between said anode and said cathode and said control electrode and said cathode inductively coupled to each other, means for connecting a dangerously high potential in one of said circuits, a circuit for deriving energy from said first-named circuits, said last-named circuit being insulated against metallic electrical conduction from said anode-cathode circuit, an amplifier having input and output circuits and common connections from said sound conversion unit and said last-named circuit to said input circuit, whereby said sound conversion unit is metallically connected to said last-named circuit.

6. A system of communication between a central station and a plurality of distributed stations

comprising unitary sound conversion units located at said distributed stations, sound conversion means located at said central station, an amplifier having input and output terminals, 5 switch means to be actuated for connecting any one of said sound conversion units either to the input terminals or the output terminals of said amplifier whereby any one of said distributed stations may transmit a message to any other 10 of said distributed stations and additional switch means for connecting said sound conversion means to said input terminals, said switch means at the same time connecting said sound conversion units to said output terminals provided said 15 first-named switch means has been actuated and regardless of whether said first-named switch means was initially actuated to connect said sound conversion units to said input terminals or said output terminals, whereby a message may 20 be transmitted from said central station to said distributed stations.

7. A system of communication between a plurality of distributed stations comprising unitary sound conversion units located at said distributed stations, an amplifier, having input and output terminals, switch means to be actuated for connecting any one of said sound conversion units either to the input terminals or the output terminals of said amplifier whereby any one of said distributed stations may transmit a message to any other of said distributed stations, an oscillation generator having input and output circuits, said input circuit being open and said output circuit being permanently connected to said input terminals and additional switch means for simultaneously closing said output circuit and connecting said sound conversion units to said output terminals whereby a signal may be transmitted from said central station to said distributed stations.

40 8. Apparatus according to claim 7 characterized by the fact that a dangerously high potential is impressed in the input circuit and the output circuit is completely insulated against metallic electrical conduction from the input circuit and the input terminals.

9. Apparatus for communication between a plurality of stations comprising sound conversion units, of the type including a permanent magnet and voice coil to be actuated in the field of said magnet, located at said stations, amplifying means to be connected to said units for amplifying the output thereof, power supply means, means for connecting said amplifier to said power supply means and means for disconnecting said amplifier from said power supply means, responsive to a failure of said amplifying means, and for connecting the voice coils of said units in parallel, whereby signaling between said units is sound powered.

60 10. A system of communication between a central station located above water and a plurality of distributed stations located under water comprising unitary sound conversion units so disposed at said distributed stations that sound may be conveniently impressed thereon for transmission or received therefrom, sound conversion means located at said central station, switching means individual to each said sound conversion unit and located at said central station providing for the transmission of a message from any one of said distributed stations to any other of said distributed stations and switching means associated with and located at said central station providing for the reception of the said mes-

sage from any one station to any other station and for the transmission of a message from said central station to said distributed stations, the last said switching means operating to permit the transmission of a message from said central station to any distributed station when the switch individual to said station is either in the receiving or transmitting position.

11. A system of communication between a central station located above water and a plurality 10 of distributed stations located under water comprising unitary sound conversion units so disposed at said distributed stations that sound may be conveniently impressed thereon for transmission or received therefrom, signaling means, 15 switching means individual to each said sound conversion unit and located at said central station providing for the transmission of a message from any one of said distributed stations to any other of said distributed stations and switch- 20 ing means associated with and located at said central station providing for the reception of the said message from any one station to any other station and for the operation of said signaling means to transmit a signal from said central station to said distributed stations, the last said switching means operating to permit the transmission of a signal from said central station to any distributed station when the switch individual to said station is either in the receiving or 30 transmitting position.

12. A system of communication between a central station located above water and at least one distributed station located under water comprising a sound conversion unit at said distributed 35 station, signaling means including a discharge device having an anode, a cathode, and a control electrode, circuits between said anode and said cathode and said control electrode and said cathode inductively coupled to each other, means 40 for connecting a dangerously high potential in one of said circuits, and a circuit for deriving energy from said first-named circuit, said last-named circuit being capable of metallic connection to said sound conversion unit and being insulated against electrical metallic conduction 45 from said anode-cathode circuit.

13. A system of communication between a central station located above water and at least one distributed station located under water comprising a sound conversion unit at said distributed stations, signaling means including a discharge device having an anode, a cathode, and a control electrode, circuits between said anode and said cathode and said control electrode and said cathode inductively coupled to each other, means 50 for connecting a dangerously high potential in one of said circuits, a circuit for deriving energy from said first-named circuits, said last-named circuit being insulated against electrical metallic conduction from said anode-cathode circuit, an amplifier having input and output circuits and common connections from said sound conversion unit and said last-named circuit to said input circuit, whereby said sound conversion unit is metallically connected to said last-named circuit.

60 14. A system of communication between a central station and a plurality of distributed stations located under water comprising unitary 70 sound conversion units so disposed at said distributed stations that sound may be conveniently impressed thereon for transmission or received therefrom, sound conversion means located at said central station, switching means individual 75

- 5 to each said sound conversion unit and located at said central station providing for the transmission of a message from any one of said distributed stations to any other of said distributed stations and switching means associated with and located at said central station providing for the reception of the said message from any one station to any other station and for the transmission of a message from said central station to 10 said distributed stations, the last said switching means operating to permit the transmission of a message from said central station to any distributed station when the switch individual to the last said station is either in the receiving or transmitting position.
- 15 15. A system of communication between a central station and a plurality of distributed stations comprising unitary sound conversion units so disposed at said distributed stations that sound may be conveniently impressed thereon for transmission received therefrom, signaling means, switching means individual to each said sound conversion unit and located at said central station providing for the transmission of a message from any 20 one of said distributed stations to any other of said distributed stations and switching means associated with and located at said central station providing for the reception of the said message from any one station to any other station and for 25 the operation of said signaling means to transmit a signal from said central station to said distributed stations, the last said switching means operating to permit the transmission of a signal from said central station to any distributed station 30 when the switch individual to said distributed station is either in the receiving or transmitting position.
- 35 16. A system of communication between a central station and at least one distributed station located under water comprising a sound conversion unit at said distributed station, signaling means including a discharge device having an anode, a cathode, and a control electrode, circuits between said anode and said cathode and said control electrode and said cathode inductively coupled to each other, means for connecting a dangerously high potential in one of said circuits, and a circuit for deriving energy from said first-named circuit, said last-named circuit being capable of metallic connection to said sound conversion unit and being insulated against electrical metallic conduction from said anode-cathode circuit. 40
- 45 17. A system of communication between a plurality of distributed stations located under water comprising a sound conversion unit at each said distributed station, signaling means including a discharge device having an anode, a cathode, and a control electrode, circuits between said anode and said cathode and said control electrode and said cathode inductively coupled to each other, means for connecting a dangerously high potential in one of said circuits, and a circuit for deriving energy from said first-named circuit, said last-named circuit being capable of metallic connection to said sound conversion unit and being insulated against electrical metallic conduction from said anode-cathode circuit. 45
- 50 18. A system of communication between a central station and at least one distributed station located under water comprising a sound conversion unit at said distributed station, signaling means including a discharge device having an anode, a cathode, and a control electrode, circuits between said anode and said cathode and said control electrode and said cathode inductively coupled to each other, means for connecting a dangerously high potential in one of said circuits, a circuit for deriving energy from said first-named circuit, said last-named circuit being insulated against electrical metallic conduction from said anode-cathode circuit, an amplifier having input and output circuits and common connections from said sound conversion unit and said last-named circuit to said input circuit, whereby said sound conversion unit is metallically connected to said last-named circuit. 50
- 55 19. A system of communication between a plurality of distributed stations located under water comprising a sound conversion unit located at each said distributed station, signaling means including a discharge device having an anode, a cathode, and a control electrode, circuits between said anode and said cathode and said control electrode and said cathode inductively coupled to each other, means for connecting a dangerously high potential in one of said circuits, a circuit for deriving energy from said first-named circuit, said last-named circuit being insulated against electrical metallic conduction from said anode-cathode circuit, an amplifier having input and output circuits and common connections from said sound conversion unit and said last-named circuit to said input circuit, whereby said sound conversion unit is metallically connected to said last-named circuit. 55
20. Apparatus according to claim 4, characterized by a transformer having at least three coils functioning to couple the circuits between the anode and the cathode and the control electrode and the cathode and to supply the energy to the circuit for deriving energy from the anode cathode circuit. 55
